IRONING MACHINE

Fred A. Conterman, Jamestown, N. Y., assignor
to Blackstone Manufacturing Company, Inc.,
Jamestown, N. Y., a corporation of New York

Application January 13, 1938, Serial No. 184,820

7 Claims. (Cl. 45—68)

This invention relates to an improvement in ironing machines and more particularly to a cabinet structure therefor.

In one form the invention discloses a table mounted ironing machine having an enclosure or cover. The cover, in one position, is adapted to enclose all that portion of the machine mounted on the table and in the other position may be conveniently utilized as a shelf and/or receptacle for the storage of freshly ironed articles or articles about to be ironed, and this, therefore, constitutes one of the objects of the invention.

Another object of the invention lies in the provision of a cover for an ironing machine which completely encloses the ironing roll and shoe when in closed position.

Another object of the invention lies in the provision of a cover for an ironing machine which is movable into open position adjacent one end of the machine.

Another object of the invention lies in the provision of a cover for an ironing machine which, when in open position, serves as a continuation or addition to the table top of the machine.

Another object of the invention lies in the provision of an ironing machine cover which, when moved into open position, lies in substantially the same horizontal plane as the table top of the machine.

Another object of the invention lies in the provision of a cover for the table top of an ironing machine which is movable through more than one plane into open position to expose the machine for use.

Another object of the invention lies in the provision of a cover for the table top of an ironing machine that is movable to expose the machine for use and also assume a position at one side of an operator of a machine for convenient use as a shelf or receptacle.

Other and further objects of the invention will be more fully understood from a consideration of the following specification, taken in conjunction with the accompanying drawings, in which

Fig. 1 is a perspective view of an ironing machine showing a cover, embodying one form of the invention, in closed position;

Fig. 2 is a perspective view of the structure shown in Figure 1, with the cover in partly opened position;

Fig. 3 is a perspective view of the structure shown in Figure 1 with the cover in fully opened position;

Fig. 4 is an enlarged plan view of the invention, parts being broken away to disclose the

support and operating mechanism of the cover;

Fig. 5 is an enlarged fragmentary end view of the hinge construction of the cover, being taken substantially as indicated at 5—5 of Figure 4;

5 Fig. 6 is an enlarged end view of an ironing machine showing the cover in fully opened position, parts being broken away to disclose the cover support and hinge structure;

Fig. 7 is an enlarged vertical sectional view 10 taken substantially on the line 7—7 of Figure 4 and shows certain details of the cover hinge construction;

Fig. 8 is a fragmentary view of the cover counter balance, the cover being in the position 15 shown in Figure 2;

Fig. 9 is a view similar to Figure 8, showing the counter balance acting to support the weight of the cover as it is moved from the position of Figure 2 to that of Figure 3; and

20 Fig. 10 shows the counter balance in position to substantially sustain the weight of the cover, when the cover is in fully opened position.

Reference is now had to the drawings which disclose one modification of the invention, generally indicated by the reference numeral 10. The ironing structure is mounted on a table 11 which includes a pair of substantially identically spaced apart members 12 and 13. These members are each formed with side walls 14 and short 25 front and rear walls 15. Members 12 and 13 are connected by a table top 16, adapted to support a rotary ironer which includes a roll 17 and supporting and driving mechanism 18. Inasmuch as the ironer may be any one of several types 30 and the mechanism thereof forms no part of the present invention, further description is deemed unnecessary.

A cover 19 is adapted to be mounted on the table top 16 and enclose roll 17 and driving 35 mechanism 18. In the present disclosure, the cover is shown to be rectangular in shape and of substantially the same lateral dimensions as the top 16. The cover 19 includes a flat table-like top 21 which, when in closed position (see Figure 1) is adaptable for use in a kitchen or elsewhere as a work surface. Secured to end 22 of the cover are brackets 23 and 24. These brackets, substantially identical, are each formed with a strap-like portion 26 which extends along the end wall 22 of the cover and is secured thereto in any suitable manner as by bolts or rivets. The strap portion of each bracket also serves to strengthen and rigidify the wall 22. Each bracket includes a lug 27 through which a transverse opening 28 is made. A rod 29 is provided at one end with a

collar 31 which has an apertured lug 32 adapted to abut the lug 27 of bracket 23. A suitable pin 33 provides for pivotal movement between rod 29 and the cover. The other end of the rod 29 is fitted with a collar 34 having an apertured lug 36 adapted to be pivotally engaged with the lug 27 of bracket 24 through the use of a further pin 33. The end of the collar 34 is formed with an angularly directed portion 37, having an opening therethrough adapted to receive one end of a shaft 38 located in and projecting beyond one end of the table 11.

Examination of Figure 4 indicates that directly beneath the top 16, the table is fitted with a pair of corner braces 39. Flanges 41 of these braces are riveted or otherwise joined to the members 12 and 13. The body portion 42 of each of the braces constitutes a bearing for the shaft 38. It will be noted that the rod 38 lies directly beneath the table top 16 and adjacent the rear edge thereof. One of the braces 39 supports one end of the shaft, whereas the other brace supports the shaft 38 adjacent its other end. The shaft extends through the end of the table and terminates in the portion 37 of collar 34.

The collar 31 is formed with a depending portion 43 through which a transverse opening is made to mount a spring pin 44. One end of the pin projects laterally beyond the portion 43 and is fitted with a knob 45. The other end of the pin projects beyond the opposite face of the portion 43 and is adapted to fit an opening in a plate 46 secured to one end of the table. It will be noted that rod 29 is fixed against inadvertent movement with respect to the table by means of its connection with rod 38 at one end and the pin connection 44 with plate 46 at the other. Thus the cover may be moved from the position shown in Figure 1 to that of Figure 2 and pivots about pins 33. With the cover in raised position, it is next necessary to withdraw pin 44 from engagement with plate 46 by manipulating knob 45. The rod 29 and cover 19 may now be swung parallel with the end of the machine and rod 38, through collar 34, serves as the pivot. It is quite evident the cover 19 will swing beyond the position shown in Figure 3 unless some support is provided therefore and in the present disclosure this support may take the form of a rubber covered projection 47 on the plate 46 and a stop-plate 48 secured to the rear corner of member 13. Plate 48 includes a flange 49 which is engaged by pin 44 when the cover is in fully opened position.

The cover 19, being substantially the dimensions of the table top 16, is of considerable size and weight and, therefore, a counterbalancing mechanism is provided which functions when the cover is moved from the position of Figure 2 to that of Figure 3. This mechanism, in one form, comprises an arm 50 having a collar mounted on shaft 38. The collar is keyed or otherwise suitably secured to the shaft and rotates therewith. The free end of arm 50 is engaged by one end of a spring 51. The other end of the spring 51 is engaged with a bracket 52 located adjacent the front of the table beneath the top 16. The tension of the spring is such it will, in conjunction with arm 50, substantially sustain the weight of the cover 19 as it is moved from vertical to horizontal position. Figure 8 of the drawings shows the position of the counterbalance when the cover 19 is in the position shown in Figure 2. When the cover is swung forwardly of the ironing

device, arm 50 rotates with shaft 38, increasing the tension of spring 51 and, as the cover moves downwardly into the horizontal position shown in Figure 3, the tension of spring 51 is greatly increased. When the cover has come to rest on the projection 47, and pin 44 abuts flange 49, the arm and spring 50 and 51 will assume the position shown in Figure 10.

It may be found desirable to provide means for retaining the cover in closed position or for assisting movement of the cover from closed to the upright position of Figure 2. This may be done by providing one or more springs 53 adjacent the pivotal end of the cover. One end of the spring 15 is secured to a pin 54 located on either or both brackets 23 and 24 and the other end of the spring is secured to a pin 56 located on sleeves 31 and 34. As indicated in Figures 5 and 7 of the drawings, the line of the spring 53 is to one side of the pivotal center about which the cover moves and consequently the spring or springs 53 function both to urge the cover into contact with the table top 16 or, when the cover has been partly raised, to urge it into the upright position of Figure 2.

When it is desired to expose the ironing mechanism for use, the operator grasps a handle or rod 57 which is secured between end brackets 58, suitably joined to the free end of the cover 19. The cover is moved from horizontal to upright position, being aided through a portion of this travel by springs 53. Knob 45 is moved to withdraw pin 44 from the plate 46 and the cover 19 may then be swung forwardly of the device, pivoting about sleeve 34 and shaft 38. During movement of the cover from vertical to horizontal position of Figure 3, the counterbalancing device above described comes into action and prevents banging or slamming of the cover. It will be noted that the cover 19 now occupies a position such that one side wall thereof has become a work surface flush with the table top 16 and also that the cover extends sufficiently forwardly of the end of the table so that the inner surface of the lower side of the cover may constitute a shelf in which to store freshly ironed articles or articles about to be ironed. It is contemplated that the cover 19 will be used practically to the exclusion of all other surfaces as a surface on which to place articles and it may on occasion be required to sustain a considerable weight. It is, therefore, found convenient to provide a leg 59 which is pivotally secured to the inner free edge of the cover by a bolt 61 that projects through one of the handle brackets 58. The leg is formed with an offset 62, the end of which is fitted with a rubber bumper 63. When the leg is swung from within the cover, into the position shown in Figure 6 of the drawings, the bumper 63 of the offset portion 62 rests against the lower side of the cover.

Although applicant has shown and described only one modification of a supporting hinge construction for an enclosure or cover for ironing machines, which functions to swing the cover into a position to be used as a work surface substantially flush with the top of the ironing machine, it will be apparent to those skilled in the art that other modifications of the structure herein disclosed may be made and are contemplated in so far as they are within the spirit and scope of the invention as set forth in the hereunto annexed claims.

Having thus set forth my invention what I

claim as new and for which I desire protection by Letters Patent is:

1. In an ironing machine having a table and an ironing mechanism mounted thereon, a cover adapted to enclose said mechanism, hinge means on said cover, a rod on said table, said hinge means being joined to and adapted to rotate said rod during opening or closing said cover, and counterbalance means connected with said rod and adapted to substantially sustain the weight of said cover in certain positions.

2. In an ironing machine having a table and an ironing mechanism mounted thereon, a cover adapted to enclose said mechanism, hinge means on said cover, said hinge means including a rod, means on said table mounting one end of said rod for pivotal movement, counterbalance means connected with the table means, the table means being rotatable by said rod to actuate said counterbalance means whereby to substantially sustain the weight of said cover during movement from one position to another.

3. In an ironing machine having a table and an ironing mechanism mounted thereon, a cover adapted to enclose said mechanism, hinges connecting said cover with a rod, means on said table mounting one end of said rod for pivotal movement transversely of said table, and further means connected with said hinges, said further means urging said cover into closed or opened position.

4. In an ironing machine having a table and an ironing mechanism mounted thereon, a cover adapted to enclose said mechanism, a rotatable rod carried by and projecting beyond one edge of said table, a further rod joined to one end of said rod, hinge means connecting said cover with said further rod, means connected with said hinge serving to urge said cover into closed or opened position, and further means adapted to substantially sustain the weight of said cover during further movement thereof.

5. In an ironing machine having a table and an ironing mechanism mounted thereon, a cover

adapted to enclose said mechanism, a rod adjacent one end of said cover, hinges connecting said rod with said cover, a further rod mounted in said table and projecting beyond one end thereof, one end of said further rod being connected with and supporting one end of the first mentioned rod, an arm secured to said further rod and rotatable therewith, a spring connecting the free end of said arm with said table, said cover being movable to a vertical position about said hinges and again to a horizontal position about said further rod, said spring being extended during movement to the horizontal position and serving to substantially counterbalance the weight of said cover.

15 6. In an ironing machine having a table and an ironing mechanism mounted thereon, a cover adapted to enclose said mechanism, a rod adjacent one end of said cover, hinges connecting said rod and said cover, means carried by and projecting beyond said table, said rod being supported at one end by said means, further means securing the other end of said rod to said table, said cover being movable with respect to said rod into open position, said further means being releasable to facilitate pivoting said cover and said rod about said table means whereby to position said cover at a height equal to or less than the plane of said table.

20 7. In an ironing machine having a table and an ironing mechanism mounted thereon, an enclosing cover for said mechanism, pivot means on said table, hinge means on said cover joined to the pivot means, said hinge means and said pivot means successively prescribing paths of movement of said cover from closed position to an open side position for use as a shelf adjacent one end of said table, an arm carried by said pivot means and rotatable therewith, a spring connected at its ends respectively with said table and said arm for variably sustaining the weight of said cover during movement in the path prescribed by said pivot means.

FRED A. CONTERMAN.
